UNITED STATES PATENT OFFICE

JOHN HEATLEY AND HAROLD ROGERS HEATLEY, OF BLACKBURN, ENGLAND

DOBBY MECHANISM OF LOOMS FOR WEAVING

Application filed March 23, 1928, Serial No. 264,183, and in Great Britain March 25, 1927.

This invention relates to improvements in or in connection with dobbey mechanism of the Keighley type such as shown in British Patent 1092 of 1867 to Hattersley, et al., employed with looms for weaving, in which double-armed swing levers have pivoted to them catches acting in conjunction with knives and jack levers are coupled to such swing levers.

10 It is of course well known to pivot the jack lever at a point above, below or to one side of the pivot of one of the catches with the swing lever.

Our invention has particular reference to 15 the type of dobbey mechanism described in British Patent No. 201,595 of which one of the present applicants, John Heatley, is a patentee, and consists in arranging the pivotal point of the jack levers on a centre line 20 co-incident with that of the lower centre line or pivotal point of the lower series of catches instead of on different centres such as is shown in the drawings of the aforesaid patent and such as is common practice in other 25 dobbey mechanism of a similar kind and to so arrange co-acting surfaces between the jack lever and the double-armed swing lever as to act in mutual support when the double-armed swing lever is being pulled forward 30 by its upper catch and whilst being returned to the initial position against the usual fixed stop for the whole series of double-armed swing levers and jack levers.

Our invention will be fully described with 35 reference to the accompanying drawing which shows a side elevation of one set of a double-armed swing lever, jack lever, upper and lower catches, pivoted arms co-acting with the free ends of the latter and the knives 40 for operating the catches, such parts being sufficient of the mechanism of the dobbey to enable the application of our invention thereto to be understood.

In the aforesaid drawing 1 indicates the 45 double-armed swing lever having an upper arm 2 to which the upper catch 3 is pivoted at 4 and a lower arm 5 to which the lower catch 5^a is pivoted at 6 whilst 7 is the jack lever having an upper arm 8 pivoted to the 50 double-armed swing lever at 9 and a lower

arm 10, the outer end which is coupled to the heald either direct or in any other usual way. 11 are the pivoted arms operated by the usual pattern mechanism and co-acting with the catches 5 and 5^a whilst 13 are the usual knives co-acting with the catches in the well known way. Hitherto the pivotal centre of each jack lever has been located some distance away from the pivotal centre of the lower catch with the lower arm of the double-armed swing lever 1. Instead of this the main feature of our present invention consists in arranging the pivotal point of each jack lever on a horizontal centre line 60 co-incident with the lower horizontal centre line or pivotal point of each lower catch and the lower arm of the double-armed swing lever. To this end we arrange the cross stay 14 running from one side frame of the dobbey to the other to constitute a fulcrum or support about which the jack levers 7 may move, such stay being preferably of substantially 65 crescent form in section and having an outer face 15 corresponding to the inner face of the jack lever. The lower arm 5 of the 70 double-armed lever 1 is cranked backwardly to pass under the hollow face of the stay 14, the end of the cranked portion having pivoted to it the rearward end of the lower catch 5^a on a centre line from which is struck 75 the outer curve of the stay 14, thus making the two centers, i. e., those of the jack lever and of the lower catch and lower arm of the lever, coincident. The lower catch may be 80 pivoted to the lower arm of the lever 1 in any suitable manner permitting of the required free movement of the catch about the centre. It will therefore be understood that when the upper catch is in engagement with the upper 85 knife the double-armed swing lever 1 and the jack lever 7 move simultaneously about the same centre with little or no friction between the pivotal centre of the lower catch and the lower arm of the lever 1. The same action 90 occurs on the backward motion of the lever 1. The boss or rear end of the lower catch is quite clear of the inner face of the stay or pivotal centre 14.

In the dobbey mechanism shown in the drawings of the aforementioned patent the 100

lower arm of the double-armed swing lever bears against a fixed bar 28 which is also employed in other similar types of dobbey and owing to the different centres of the jack lever and the lower catch connection of the double-armed swing lever, the lower arm of said swing lever rises and falls slightly in contact with the bar 28 as the upper arm of the lever is pulled forward by the upper catch, thus setting up friction. This friction is entirely eliminated by the arrangement constituting our invention.

In order that the jack lever 7 shall keep in contact with the double-armed swing lever 1 during the forward and backward movements of the upper arm of the lever due to the action of the upper catch, it is provided with a projecting side face 16 which bears against a flange 16^a on the rear of the lower arm 5 about midway between the pivotal centre of the lower catch and the pivotal centre 9 of the jack lever and the swing lever. This side face 16 acts as a stop for the lower arm 5 of the swing lever 1 on the completion 25 of the backward motion of such lower arm after the lower catch has been released from the lower knife. During operation of the double-armed swing lever by the lower catch, the upper end of such lever bears against 30 the usual stationary bar 28 (which acts as a fulcrum) arranged across the dobbey against which the upper arms of the swing levers 1 may normally rest. A roller 26 as referred to in the aforementioned patent may also be 35 employed as a fulcrum for the purpose.

The face 16, formed upon the jack lever 7, is in contact with the double-armed swing lever 1 at all times except when the lower catch 5^a operates upon the double-armed 40 swing lever 1. When the jack lever 7 is at rest as shown in the drawing neither of the catches 3 or 5^a being engaged by their respective draw-knives 13 it is supported by the combined cross stay and fulcrum 14 and 45 also by the joint or fulcrum 9 of the swing lever 1. The swing lever 1 is enabled to support lever 7 at the joint or fulcrum 9 by means of the face 16 of lever 7 and by the cross bar 28 against which it rests.

50 Assuming the jack lever to be at rest as shown in the drawing if the top catch is drawn forward by its knife 13 the swing lever 1 will be prevented from turning upon its fulcrum 9 by the projection 16 upon the face 55 of jack lever 7 and the swing lever 1 will, along with the jack lever 7, turn or partly revolve about the fulcrum 6 upon the crescent shaped bar 14. Again assuming the jack lever to be at rest as shown in the drawing, if the 60 bottom catch is drawn forward by its knife, the swing lever in turning upon the fulcrum 9 will heel against the top cross bar 28 and the jack lever will again turn or partly revolve about the fulcrum 6 upon the crescent shaped 65 bar 14. If the catches are operated alternate-

ly the fulcrum 9 will be kept in its forward or drawn out position, the swing lever will oscillate upon its fulcrum 9 and the jack lever will be retained in its lifted position.

More than one stop member may be provided between the swing lever 1 and the jack lever 7 as shown on the drawing at 16, 16^a, A, B and C. All that is needed, is that the swing lever 1 shall only be able to turn from its normal position (that is, the position shown in the drawing in which neither of the catches has been operated to move the swing lever), by moving upon the fulcrum 9 of the lever 7 in one direction, that is, in the direction as it may be operated by the bottom catch. When operated by the top catch only, the swing lever cannot turn upon its fulcrum 9 being prevented by the stop or stops referred to, it and the jack lever 7 moving together as though in one piece.

80 It will be understood that the invention is not limited solely to the form of construction shown, but that it may be modified in many ways within the scope of the appended claims.

85 The arrangement hereinbefore described 90 enables the dobbey generally to be less in height and less in length, in proportion to the dimensions of swing lever 1 in the latter case when shorter jack levers are employed to get the same lift on the heads as with the ordinary longer jack levers, whilst at the same time making for easier movement of the mechanism.

95 We declare that what we claim is:—

1. A dobbey mechanism for dobbies of the Keighley type comprising in combination 100 double arm swing levers, catches pivoted to said swing levers and jack levers pivoted on an axis coincident with the pivot of one of said catches.

105 2. A dobbey mechanism for dobbies of the Keighley type comprising in combination double arm swing levers, catches pivoted to said swing levers and jack levers pivoted on an axis coincident with the pivot of one of 110 said catches, and a fixed pivotal support for the pivot for said jack levers of crescent shape cross section to permit one end of the swing lever to pass into it.

115 3. A dobbey mechanism for dobbies of the Keighley type comprising in combination double arm swing levers, catches pivoted to said swing levers and jack levers pivoted in an axis coincident with the pivot of one of said catches, and an abutment projecting from 120 each jack lever adapted to engage the double arm swing lever, so that the jacks and double arm swing levers move together under the action of the usual catches and knives at all times except when the double arm swing levers 125 upon the double arm swing levers.

In witness whereof, we have hereunto signed our names this 8th day of March, 1928.

JOHN HEATLEY.

HAROLD ROGERS HEATLEY.
